UNITED STATES PATENT OFFICE.

DANIEL MERCIER, OF ANNONAY, ARDECHE, FRANCE.

MACHINE FOR THE TREATMENT OF SKINS AND LEATHER.

1,411,056.

Specification of Letters Patent. Patented Mar. 28, 1922.

Application filed June 29, 1921. Serial No. 481,208.

To all whom it may concern:

Be it known that I, DANIEL MERCIER, a citizen of the French Republic, residing at Annonay, Ardeche, in the Republic of France, have invented new and useful Improvements in Machines for the Treatment of Skins and Leather, of which the following is a specification.

This invention relates to a machine for the treatment of skins and leather and is characterized chiefly in that it comprises two endless aprons or belts moving in the same direction and entering in contact with each other upon a certain portion of their length constituting the active portion of the two aprons between which is engaged the skin under treatment, one of the said aprons being provided with blades and the other with air-inflating cushions, the said aprons being caused to press upon each other at stated intervals at various points of their active surfaces in such manner as to hollow and to bend the said skin at the same time that it is stretched by the machine. Other features of the invention will be set forth in the following description.

The accompanying drawings show by way of example various embodiments of this invention.

Fig. 1 is an elevational view of a machine for the treatment of skins of leather according to this invention.

Fig. 2 is a corresponding plan view, with the upper part of the machine removed.

Fig. 3 is an elevational view of a modified form of construction of the said machine.

Fig. 4 is an end elevation of the machine as viewed from the left hand side, this being a diagrammatic and partial view.

Fig. 5 is a detail view showing the device for securing the blades to the lower apron.

Fig. 6 is also a detail view, showing the construction of the air-inflated cushion.

As shown in Figs. 1 and 2, the frame of the machine is constituted by two parallel cast-iron side-pieces 1 which are cross-connected by suitable members. On the lower part of the machine are mounted the rollers 5, 6 and 7 between the side-pieces 1. The

said rollers have disposed thereon an endless apron 2 formed by a chain, a belt, or a belt assembled with a chain. Upon the said apron or conveyor 2 are disposed the blades 3 having a suitable cross section and

properly spaced apart. The roller 5 is used to actuate the apron 2 and is driven by the pulleys 4 through the medium of the gear wheels 8 and 9. The roller 7 serves for stretching or tightening purposes, and it may be raised or lowered by the hand-wheel 11 operating a screw 10 and a forked member 12 carrying the roller 7. At the front part of the machine is a sheet metal cover 13 placed over the apron 2 where the latter passes over the first roller 6. The auxiliary rollers 14, 15, 16 of the apron 2 are mounted loose on their axles, these latter being stationary with reference to the side pieces 1.

At the upper part of the machine, the rollers 17, 18, 19 are mounted between the side-pieces. A pivoted frame is formed by the parallel inclined links 50 which are pivoted to the axles of the rollers 17, 18, 19 and by the horizontal connecting bars 51 having journaled thereon the rollers 20, 21, 22. The rollers 17 to 22 have disposed thereon the apron 23 which is constituted by a belt, a chain, or a belt and chain combined. Upon the said apron are mounted the small air-inflated cushions 24 which are suitably spaced apart. The pivoted frame 50, 51 is given a reciprocating movement by means of a pair of links 26 actuated by a lever 27 pivoted to an axle 52 and carrying at the lower part thereof a roller 28 co-operating with the cam 29. This cam 29 is actuated by suitable means, for instance by a chain disposed upon the sprocket wheels 30, 31. The roller 19 actuates the apron 23 and is driven by the pulleys 4 through the intermediary of the gear wheels 8, 8^a, 32. The roller 18 serves as a stretching device by the use of the hand-wheel 33. The swinging lever 27 is provided with a longitudinal slot 34 through which the pivot 52 is adapted to extend and in this manner the said lever may be raised or lowered, thus changing the effective length of the lever arms and consequently the stroke of the links 26. The said lever is raised and lowered by the pin 35 disposed upon the said lever and actuated by the lever 36 which engages the quadrant 37.

In the lower position of the bars 51 of the pivoted frame, that is, in the operative position, the pressure exerted by the upper rollers 20 to 22 is never brought to bear upon the lower rollers 14 to 16, but at points

situated between the latter, thus obviating all contact between hard or rigid parts. On the contrary, by means of this disposition all the rigid parts of the upper apron 5 are in contact with the flexible parts of the lower apron, and vice versa, the rigid parts of the lower apron are in contact with the flexible parts of the upper apron. Instead of providing an automatic control for the 10 links 26 by cam, crank or the like, as herein described, the control may be carried out by hand or by pedal, by the use of suitable levers acting upon the said pivoted frame.

The operation of the machine is as follows:

When the roller 28 enters in contact with the lower part of the cam 29, the bars of the pivoted frame are driven to the left, Fig. 1, in such manner that the rollers 20, 20 22 and the lower part of the apron 23 are raised, and the latter is now sufficiently separated from the lower apron 2 to permit the operator to introduce the skin between the two aprons, holding it by his body 25 against the cover 13. The skin is held by the hands at each side of the machine at 39, Fig. 4. When the cam has rotated to drive forward the roller 28 moving the links 26 to the rear, the rollers 20, 21, 22 will descend causing the inflated cushions 24 of the upper apron 23 to bear upon the skin on one side, while the blades 3 of the lower conveyor 2 will bear upon the skin from underneath.

35 The active parts of the two aprons 2 and 23 are caused to move at the same speed and in the same direction, or according to the arrow, and consequently the effect of the cushions 24 is added to that of the blades 3 to draw the skin towards the right hand side, Fig. 1. Each of the cushions 24 cooperates with the blades 3 situated under the same, whence the skin is not only stretched but also rendered more flexible. 40 Each time that the machine is opened by means of the cam 29, the skin is moved in such manner as to treat the whole surface by such operations.

It will be understood that when the lever 50 27 is moved lengthwise upon the pin 52, this will change the amount of movement of the links 26 and consequently the pressure of the roller 20, 21, 22 upon the blade-carrying apron 2. The pressure may thus be made 55 greater or less according to the character of the skins under treatment.

In the modified form of construction shown in Fig. 3, the rollers supporting the upper apron 23 are mounted on a frame 56 pivoted at 57 to the machine frame and provided with an arm 56^a carrying a counter-weight 58. This frame 56 is given a swinging motion by means of the sliding lever 27^a which is vertically guided upon the machine frame and is pivoted to the arm 56^a.

The lever 27^a is provided with a roller 28 engaging the cam 29. The operation is substantially the same as in the preceding case. The pressure is varied by the stretching roller 44 mounted upon the lever 12^a which is pivoted to the frame 56.

In both these constructional forms, a clutch of any known type may be used to momentarily stop the action of the cam 29 and to leave the machine in the open position.

The inflated cushions 24 may be constituted by an air chamber of suitable form provided with an outer covering. However it is preferable to make use of four, six or 80 eight balls 40, Fig. 6, of the tennis ball type, which are suitably disposed in flexible mounting such as felt, leather, or the like and surrounded by the leather covering 41. This assemblage is secured to the apron by 85 nails or fasteners 42, 43.

Having now described my invention, what I claim as new and desire to secure by Letters Patent is:

1. A machine for treating hides, skins 90 and leather, comprising two endless aprons adapted to cooperate by parts of their length which form the active portions of said aprons, the skin being inserted between said active portions, means for supporting and driving said aprons whereby they will move in the same direction in their active portions, blades on one apron, air cushions on the other apron and means for alternately separating the active portions of the 100 aprons and pressing the active portion of one apron against the active portion of the other apron at spaced points thereof.

2. A machine for treating hides, skins and leather, comprising two endless aprons 105 adapted to cooperate by parts of their length which form the active portions of said aprons, the skin being inserted between said active portions, means for supporting and driving said aprons whereby the same will move in the same direction in their active portions, blades on one apron, air cushions on the other apron, two series of rollers supporting the active portions of said aprons, respectively, the rollers in one series being in 110 a staggered disposition with respect to the rollers in the other series, and means for alternately causing the series of rollers to recede from or come nearer to each other.

3. A machine for treating hides, skins and 120 leather comprising two endless aprons adapted to cooperate by parts of their length which form the active portions of said aprons, the skin being inserted between said active portions, means for supporting and driving said aprons whereby the same will move in the same direction in their active portions, blades on one apron, air cushions on the other apron, two series of rollers supporting the active portions of said aprons 125 130

respectively, the rollers in one series being in a staggered disposition with respect to the rollers in the other series, a rotary cam and means operated by said cam for alternately 5 moving one series of rollers towards the other series and away from said other series of rollers.

4. A machine for treating hides, skins and leather comprising two endless aprons 10 adapted to cooperate by parts of their length which form the active portions of said aprons, the skin being inserted between said active portions, means for supporting and driving said aprons whereby the same 15 will move in the same direction in their active portions, blades on one apron, air cushions on the other apron, each of said air cushions comprising hollow elastic balls and a flexible mounting for holding the same 20 together, two series of rollers supporting the active portions of said aprons respectively, the rollers in one series being in a staggered disposition with respect to the rollers in the other series, a rotary cam and 25 means operated by said cam for alternately moving one series of rollers towards the other series and away from said other series of rollers.

5. A machine for treating hides, skins and 30 leather comprising two endless aprons adapted to cooperate by parts of their length which form the active portions of said aprons, the skin being inserted between said active portions, means for supporting and 35 driving said aprons whereby the same will move in the same direction in their active

portions, blades on one apron, air cushions on the other apron, two series of rollers supporting the active portions of said aprons respectively, the rollers in one series being 40 in a staggered disposition with respect to the rollers in the other series, coupling bars upon which the rollers in one series are rotatably mounted, parallel links pivoted at fixed points and connected to said coupling bars, an oscillating lever, a pivot for the same, connecting rods for connecting said oscillating lever to the coupling bars, a rotary cam adapted to act upon said oscillating lever and means for shifting the pivot 45 of said lever along the latter.

6. A machine for treating hides, skins and leather, comprising two endless aprons adapted to cooperate by parts of their length which form the active portions of 50 said aprons, the skin being inserted between said active portions, means embodying two series of rollers for respectively supporting the aprons, and driving the same whereby they will move in the same direction in their 55 active portions, the rollers which support the active portion of one apron being in a staggered disposition with respect to the rollers which support the active portion of the other apron, blades on one apron, air 60 cushions on the other apron, an oscillating frame supporting one of the said series of rollers and a rotary cam operatively connected to said oscillating frame.

In testimony whereof I have signed my 70 name to this specification.

DANIEL MERCIER.
